UNITED STATES PATENT OFFICE.

ALBERT J. LOEPSINGER, OF PROVIDENCE, RHODE ISLAND.

ART OF BURNING LIQUID FUEL.

Original application filed April 19, 1923, Serial No. 633,135. Divided and this application filed January 4, 1928. Serial No. 244,408.

This invention relates to improvements in the art of burning liquid fuel. More particularly it is useful for burning oil fuel such as petroleum distillates of the order of kerosene, or less volatile oils, to the end that these may be handled with the simplicity, quietness and safety which are desirable in domestic apartments.

Several important advantages are incident to use of my improved process, among which are, in general, and as compared with processes heretofore proposed for burning liquid fuel, the elimination of preliminary heating for vaporizing; the avoidance of blasts of steam and compressed air for atomizing; and with these a freedom from the roar that accompanies combustion wherever vapor, steam or compressed air participates; also the production of flame at substantially atmospheric pressure. In consequence, the liquid fuel may be handled with the convenience of gaseous fuel, but without the problems and incidents which are attendant upon actually converting it to gaseous form.

The process of the invention "atomizes" liquid fuel by mechanical power at a distance from the flame; that is, it breaks it into particles so small as to be capable of floating in air as a fog, and then conveys these to the burner by flotation in relatively quiet air, which is insufficient to permit of the combustion of the floating matter. Inasmuch as the fuel does not meet the air which is to carry it until the body of liquid has already been dispersed, it follows that the energy for accomplishing its dispersal does not have to be carried by the air, as in those processes heretofore known where a blast of air or steam rushing past a small opening has to disperse the solid stream of liquid which is fed thereto. Therefore the relative quantity of air can be limited to that which is needed or desired for flotation of the dispersed fuel. And the ratio of air to the fuel carried by it can be controlled so that the slowly moving current has not enough air in proportion to its burden of fuel to support the combustion. This insufficiency of air assures safety. The arranging of the fuel in a state of colloidal suspension as a fog permits of its remaining indefinitely in the air even though the air be moving very slowly indeed or even be stationary in the conduit, or in some pocket or chamber along its course. The slow flow gives quietness of combustion. And

the gas-like fluidity of the mixture, coupled with its slowness of motion, permits the location of the fog-generating means at any convenient distance or direction from the flame. Also it permits of a single fog-generating means being used to serve a plurality of furnaces. And it makes simple and silent burning apparatus available for heaters of the larger sizes and for burning the less volatile or so called "heavier" oils.

In my pending application for patent, Serial No. 633,135, filed April 19, 1923, of which this application is a division, I have disclosed and claimed apparatus which is suitable for practicing the present invention, like that here shown. However, other means may be employed for carrying the invention into effect. It is intended that this patent shall cover, by suitable expression in the appended claims, whatever features of patentable novelty exist in the art disclosed.

The accompanying drawing shows an elevation, partly in section, somewhat diagrammatic, of apparatus for practising the invention.

The shaft of a small electric motor 10 carries a fan 12 and rotor disk 13; and the edge of the disk travels close to an annular series of impact spatter blades 14, rigidly fixed around its periphery, interiorly of a dished casing 16. The region of the peripheral edge is open into the entrance 18 of a main conduit 18 whose vestibule surrounds the casing 16 at a little distance, sufficient to let air be drawn into the duct close to the edge of the rotor 90 and to the blades as at 21. A gentle draft is here caused by suction suitably induced at a point farther along the duct as by the injection of the air blast from the said fan. This blast through pipe 22 to annular chamber 24 surrounding the duct 18, is jetted into the duct through openings 26, in a conical partition 28, in directions leading to the burner grid 30 within the firebox of the furnace. The parts described may be arranged in any convenient relation to the firebox; but the wall 32 of the latter is shown just beyond where the annular chamber 24 surrounds the main duct 18.

With the motor in operation, turning the fan and rotor, raw liquid fuel is fed by any suitable means, for which gravity is indicated in the drawing, through a pipe 34 to the conical hub of the rotor, from which it spreads in the form of a thin film over the rotating disk.

From the periphery of the disk it is thrown by centrifugal force against the fixed blades; and by impact therewith it is pulverized into tiny particles which float off in the air like a fog. These particles are carried along the main duct 18 toward the burner by the gentle current of air which is entering through the annular port 21, the stream being gradually contracted by the converging bell walls 18^a until it enters the cylindrical portion 18^b. This slow moving current in the duct 18 has not enough air to support combustion of the rich load of liquid fuel particles, which are dispersed through it. As the main body is air it may be regarded as analogous to a body of illuminating gas which it resembles in behavior, as the presence of the small globules of liquid fuel floating dispersed in the air does not alter the gaseous behavior of the mass as a whole. Such vaporization as the liquid fuel has undergone at this stage, if any at all, is inconsiderable and is purely incidental. The injection of supplemental air into the stream of fuel, which, in the gas analogy above proposed, compares with the customary introduction of primary air of combustion, occurs at the entrance of the main duct into the furnace firebox, where the duct is somewhat enlarged, having walls 28 which constitute a conical perforated partition from the primary air supply chamber 24. This enlargement is at once reduced by the sloping portion 18^c of wall just beyond, whose convergence increases the velocity of flow so that the speed at which the then combustible mixture enters the burner box 36 under the grid, is greater than the speed of propagation of the flame backward. This controlled relation of velocity of flow prevents backfire and makes the apparatus safe from such danger. The velocity of flow may be increased by increasing the pressure in the chamber 24 thus causing the primary air jets to enter the current of fog at a greater speed, the blower 12 being made large enough to supply such air and speed as are needed.

The speed and amount of air delivered to the conduit 18 from the fan may be regulated by a damper 36 placed in the pipe 22. In the type of blower illustrated the partial closing of damper 36 will merely cause less air to be passed through to blower.

The relatively low velocity of the current issuing through the burner produces a long, lazy and silent flame, usually rather longer than that represented in the drawing, in contra-distinction to the roaring flame of the forced draft type of burners. The flame burns the minute dispersed and floating liquid droplets, without smoke, without noise, and with substantially complete combustion.

If the pipe 34 delivers fuel beyond the amount which is atomized and carried away by the rotor blades and air current, the excess drains from the sloping walls of the belled

end 18^a of the conduit and may be entrapped by suitable means (not shown) and be again placed in the liquid supply.

I claim as my invention:

1. The art of burning liquid fuel comprising the converting of the fuel into finely divided liquid particles capable of floating in air; the dispersing of the fuel particles through a body of air suitable in quantity to float said fuel and to make therewith a non-combustibly rich mixture; and the conveying of said liquid particles to the burner by slow movement of the air in which they are floating. 70

2. The art of burning liquid fuel comprising the converting of the fuel into finely divided liquid particles capable of floating in slowly moving air; the dispersing of the fuel particles through a body of air suitable in quantity to float said fuel and to make therewith a non-combustibly rich mixture; and the conveying of said liquid particles to the burner by movement of the air in which they are floating; and the discharging of the mixture at the burner at a pressure close to atmospheric pressure, for combustion. 80

3. The art of burning liquid fuel comprising the forming of the fuel and of air, within a confined space at a distance from the burner, into a fog characterized by the tendency of the particles of fuel held in suspension therein to become uniformly dispersed throughout the body of air which is within said confined space; and then guiding to the burner said fog of confined air and dispersed fuel. 95

4. The art of burning liquid fuel comprising the confining and slow moving of a current of air to the burner; the dispersing of the fuel, into suspension in said air, by a force other than that of the air current; the floating of the fuel in liquid form by the air current to the burner; and the adding of air for combustion at the burner. 100

5. The art of burning liquid fuel comprising the producing of a slow moving current of air to the burner, at approximately atmospheric pressure, and confining it to a definite path in so moving; the breaking up of the liquid fuel by spattering into particles so small as to be capable of floating in said air, and the dispersing of said particles through said air, whereby it is floated to the burner. 110

6. The art of burning liquid fuel, comprising the atomizing of the liquid in which air is at approximately atmospheric pressure; the producing of a current of air slowly moving to the burner; and the dispersing of the atomized particles through and the floating of them in the slowly moving current of air wherewith they form an incombustibly rich mixture and whereby they are conveyed to the burner. 120

7. The art of burning liquid fuel having a viscosity and a uniform colloidal dispersi- 130

bility of the order of kerosene which consists in converting it into a colloidal suspension of the fuel in liquid state in air; and conveying it to the burner in the air as a vehicle in which it is thus dispersed.

8. The art of burning liquid fuel which consists in converting it into a colloidal suspension of the fuel in liquid state in air; and

conveying it to the burner in the air as a vehicle in which it is thus dispersed; the quantitative relations of fuel and air being a mixture which is non-combustibly rich.
